United States Patent

Des. 238,613

Patented Jan. 27, 1976

238,613

PHOTOGRAPHIC CAMERA

Heinz Waaske, Mascherode, Germany, assignor to Rollei-Werke Franke & Heidecke, Braunschweig, Germany

Filed Mar. 1, 1974, Ser. No. 447,279

Claims priority, application Germany Sept. 7, 1973

Term of patent 14 years

Int. Cl. D16—01

U.S. Cl. D61—1 B

FIG. 1

FIG. 2

FIG. 3

FIG. 4

FIG. 5

FIG. 6

FIG. 7

FIG. 1 is top plan view of a photographic camera in an extended condition, showing my new design;

FIG. 2 is a front elevational view thereof;

FIG. 3 is a right elevational view thereof;

FIG. 4 is a bottom plan view thereof;

FIG. 5 is a left elevational view thereof;

FIG. 6 is a rear elevational view thereof; and

FIG. 7 is a perspective view of the design of FIG. 1 shown in a compact position.

I claim:

The ornamental design for a photographic camera, substantially as shown.
